CLAIM

The ornamental design for a bottle rack or similar article, as shown.

DESCRIPTION

FIG. 1 is a rear and left side perspective view of a bottle rack or similar article showing my new design;

FIG. 2 is a top plan view;

FIG. 3 is a front elevational view; and

FIG. 4 is a right side elevational view thereof.

FIG. 2-4 have been shown on a reduced scale with respect to FIG. 1.

FIG. 1

FIG. 2

FIG. 3

FIG. 4
